UNITED STATES PATENT OFFICE.

JUSTIN PARMELEE, OF CHICAGO, ILLINOIS.

APPLIANCE FOR THE ART OF MOLDING.

SPECIFICATION forming part of Letters Patent No. 374,000, dated November 29, 1867.

Application filed December 13, 1866. Serial No. 221,438. (No model.)

To all whom it may concern:

Be it known that I, JUSTIN PARMELEE, of Chicago, in the county of Cook and State of Illinois, have invented new and useful Improvements in Appliances for Molding; and I do hereby declare that the following is a full, clear, and exact description thereof, reference being had to the accompanying drawings, making part of this application.

My present invention relates to appliances for practicing or to the apparatus used in practicing a novel mode or method of making sand molds for casting hollow articles, (such as pipe-connections, &c.,) which novel mode or method of casting is made the subject of another application for Letters Patent by me, No. 221,437, filed simultaneously with this case; and my said present invention consists in an apparatus or contrivance comprising follow-boards and half-flasks of the peculiar construction and adapted to work together in the particular manner that will be hereinafter more fully explained, and which will be distinctly pointed out and clearly defined in the claims of this specification.

To enable those skilled in the art to which my invention relates to make and use a contrivance embracing my present improvements I will now proceed to more fully describe the latter, referring by letters to the accompanying drawings, which form a part of this specification, and in which I have shown my improvement carried out in that form in which I have so far successfully practiced it, and which is about the best form now known to me.

In the drawings, Figure 1 is a perspective view of one of two follow-boards, of novel construction, that compose parts of my improved contrivance. Fig. 1^a is a view showing a half-pattern applied to one of the follow-boards. Fig. 2 is a perspective view of one of a pair of metallic half-flasks constituting parts of my improved apparatus. Fig. 3 is a view showing the arrangement together of one of the follow-boards, one of the half-flasks, and an ordinary rolling board or bottom board that compose parts of my novel apparatus. Fig. 4 is a view showing the arrangement together of one of the half-flasks, one of the half-patterns, and an ordinary core-arbor, (for supporting the sand core,) with the flask filled to form a half-mold.

In the several figures the same parts will be found designated by the same letters of reference.

My improved apparatus comprises two follow-boards, A, in connection with which are employed the hollow half-patterns (preferably made of metal) of the article to be cast—such, for instance, as seen at B, which is a half-shell or half-pattern of a pipe elbow or coupling, two metallic half-flasks, C, and an ordinary rolling-board or bottom board, I, in addition to which may be used—in molding such sand cores as require some internally-arranged supporting device—a core-arbor, such as seen at E.

The main peculiarity of or the novel structural feature in the follow-boards A is the construction of each with a simple plane pattern-supporting surface adapted to support the pattern (such, for instance, as seen at B) with its convex exterior uppermost, for the purpose of forming thereon one half of the sand mold proper. Each of said follow-boards has projecting devices m, which engage with the edges of one of the metallic half-patterns B, for the purpose of holding said pattern B in place laterally on the board when placed thereon, and also pins o, (or their equivalents,) for regulating the relative position of each of the half-flasks C on its follow-board, while the said half-flasks have register-pins, by which the proper relationship of the flasks to each other is assured, in a manner well known.

The half-flasks C, which are preferably made of metal, being duplicates in construction, a description of one will answer for both. The half-flask C is formed or provided, as clearly shown, with a semi-cylindrical core-supporting device, c, at each end, projecting inwardly from the wall of the flask, and of a size and shape such that its semi-cylindrical end corresponds exactly with the semicircular end of the half-pattern B, and the size of the flask and the position and extent of projection inwardly of each of said devices c are such that when the half-pattern B shall have been molded in the half-flask, as seen at Fig. 4, the ends of the curved rim-like devices c will not quite meet or touch the ends of the pattern, though coinciding or being in line therewith. It is important that this relationship of the inner ends of the pattern to the adjacent devices c be observed, so that, as seen at Fig. 4, there

shall be a thin stratum of sand left between the adjacent ends of the pattern and said devices *c*, in order that after the removal of the metallic pattern *B* the perimeter or wall of the 5 mold thereof shall be composed wholly of sand, to thus prevent the possibility of the hot metal (to be poured into said mold) coming into contact with the inner ends of the metallic devices *c*. Of course, if the pattern be of a different 10 shape from that shown, the contour of the projecting devices *c* must be correspondingly different, the function and effect of these devices *c* being to project inwardly and near to the pattern end and conform in shape therewith, 15 so as to form continuations, as it were, of the interior concave and exterior convex surfaces of the pattern, to support the sand used, both while forming the sand mold and the sand core, all as will be presently further explained. 20 In the use of a contrivance or apparatus such as shown (for the purpose of practicing the improvement in the art of molding that is made the subject of my said other application) the parts or devices hereinbefore referred to, 25 and shown in the drawings, are worked or manipulated about as I will now explain. I take one of the follow-boards *A*, (see Fig. 1,) and having adjusted thereon one of the half-patterns *B*, with the convex surface of the latter 30 uppermost, as shown at Fig. 1*, I next place in proper position on the follow-board, and surrounding said half-pattern, one of the metallic half-flasks *C*, the inwardly-projecting devices *c* of said flask coming in line with the 35 ends of the metallic pattern and nearly meeting the same, as seen at Fig. 4, where the parts have been turned over after the formation of the mold. I then fill in this flask with sand, which of course rests upon the metallic 40 pattern *B* and on the devices *c*, which latter practically constitute continuations of the ends of said pattern, and having rammed the sand down well, in the usual manner, I then "strike off" the sand, and, after having sprinkled it 45 over, apply on top of the sand and half-flask a plain rolling-board—such as seen at I—so that the apparatus presents the appearance seen at Fig. 3. The parts thus arranged are then all turned over or upside down and the follow-board *A* removed, leaving the half-pattern *B* embedded in the sand within the half-flask, the 50 top edges of said pattern being of course perfectly flush or on a level with the top edges of the flask, as seen at Fig. 4. I now fill in the interior of the pattern *B*, and also the interiors of the inwardly-projecting rim-like devices *c* of the flask, with sand, for the purpose of forming one half of the core, in doing which it will be seen the sand (to form the core) is firmly supported at the projecting end portions of the core by means of the devices *c*. The pattern 55 itself, however, will have been previously rapped, so as to subsequently get a better "lift," which operation is not possible, as is 60 well known, with the old mode of molding and with the old appliances, because of the core being in the pattern from the beginning of the

molding operations. The operations just described are now repeated with the duplicate follow-board, flask, and roll-over board, and 70 with the other half of the metallic pattern, except that a core-arbor, *E*, (such as usually employed,) is inserted within the other half-pattern and the concave portions of the devices *c* in forming the last half of the sand 75 core, for purposes well understood, and in listing the flask containing this last half of the mold and the last-made half of the core (in order to place it on top of the other flask) the ends of the said core arbor may be conveniently held by the fingers of the attendant, thus not only preventing any possible "drop" 80 of the core, but also insuring the proper holding up of the metallic pattern in place while handling the flask. The two flasks having 85 now been properly put together, the last-mentioned flask is lifted off and laid one side, thus exposing the upper half of the two half-patterns, which upper half pattern is then rapped and lifted off, exposing one half of the finished core and the sand surface of the lower half-flask. After this the half-flask that was 90 removed is put back into its former relationship with the other flask and its contents, and after the application on top of a rolling-board 95 the combined parts or appliances are all turned upside down, when, with a sprue-cutter or hollow tube, a hole is made down to the metal gate (fastened on the remaining half of the pattern) and the other half-flask (which is 100 now on top) is lifted off, and the other half-pattern, after having been properly rapped, is removed. The edges of the walls of the mold are then wetted and the well-hole is blown 105 out, after which the two parts of the flask are reunited ready for the pouring operation.

In putting the parts of the flask together they are secured in the proper relative position, as usual, by means of the common clamping devices applied to the lugs *e*, after which 110 the guide-pins or steady-pins are knocked out, to be reused with another duplicate set of devices for molding another pattern.

What I claim as new, and desire to secure by Letters Patent, is—

1. A half-flask formed or provided with inwardly-projecting sand-supporting devices *c*, constructed and operating in substantially the manner and for the purposes hereinbefore set forth.

2. The combination, for the purposes of forming a complete sand mold and core, of a set of plane-surfaced follow-boards, a pair of flasks, each one of which is formed or provided with inwardly-projecting devices, *c*, and 120 suitable rolling-boards or bottom boards, the whole adapted to operate in the manner hereinbefore described.

In witness whereof I have hereunto set my hand this 28th day of October, 1886.

JUSTIN PARMELEE.

In presence of—

JNO. CLIFFORD,
W. S. VERITY, Jr.
